(57) **CLAIM**

The ornamental design for a angle cut screw-in adjustable head ground spike, as shown and described.

DESCRIPTION

FIG. 1 is a front view of the angle cut screw-in adjustable head ground spike;

FIG. 2 is a back view of the angle cut screw-in adjustable head ground spike;

FIG. 3 is a left-side view of the angle cut screw-in adjustable head ground spike;

FIG. 4 is a right side view of the angle cut screw-in adjustable head ground spike;

FIG. 5 is a top view of the angle cut screw-in adjustable head ground spike;

FIG. 6 is a bottom view of the angle cut screw-in adjustable head ground spike;

FIG. 7 is a perspective view of the angle cut screw-in adjustable head ground spike;

FIG. 8 is a front view of an alternate embodiment of the angle cut screw-in adjustable head ground spike;

FIG. 9 is a back view of an alternate embodiment of the angle cut screw-in adjustable head ground spike;

FIG. 10 is a left-side view of an alternate embodiment of the angle cut screw-in adjustable head ground spike;

FIG. 11 is a right side view of an alternate embodiment of the angle cut screw-in adjustable head ground spike;

FIG. 12 is a top view of an alternate embodiment of the angle cut screw-in adjustable head ground spike;

FIG. 13 is a bottom view of an alternate embodiment of the angle cut screw-in adjustable head ground spike; and,

FIG. 14 is a perspective view of an alternate embodiment of the angle cut screw-in adjustable head ground spike.
